UNITED STATES PATENT OFFICE.

HENRY KLECKLER, OF BUFFALO, NEW YORK.

HYDROPLANE WING-PONTOON.

1,197,746.

Specification of Letters Patent. Patented Sept. 12, 1916.

Application filed September 18, 1915. Serial No. 51,453.

To all whom it may concern:

Be it known that I, HENRY KLECKLER, a citizen of the United States, residing at Buffalo, in the county of Erie and State of New York, have invented certain new and useful Improvements in Hydroplane Wing-Pontoons, of which the following is a specification.

The present invention relates to improvements in wing pontoons for hydroaeroplanes and as its particular object contemplates the provision of a pontoon of this character which will be constructed to offer the minimum head resistance both to the water and to the air, while also possessed of the requisite strength and practicability of construction.

A further object of my invention is to equip a substantially streamline pontoon with means adapted to absorb the shock of its impact with the surface of the water, when the hydroaeroplane alights on the latter.

The above and additional objects of a similar nature which will be hereinafter more specifically treated are accomplished by such means as are illustrated in the accompanying drawings described in the following specification and then more particularly pointed out in the claims which are appended hereto and form a part of this application.

With reference to the drawings wherein there is illustrated the preferred embodiment of this invention, as it is reduced to practice, and throughout the several views, of which, like characters of reference, designate similar parts:

Figure 1 is a perspective view of a hydroaeroplane in flight, as observed from below, disclosing an equipment of pontoons such as are provided by the present invention. Fig. 2 is a detail view of the pontoon, *per se*, the forward portion being in longitudinal section and the remainder being shown in elevation. Figs. 3—4 are transverse sectional views from the forward and rear portion of the pontoons, respectively, being taken on the planes, included by the lines 3—3 and 4—4, Fig. 2. Fig. 5 is an enlarged fragmentary and sectional detail taken longitudinally through the prow cap of the pontoon. Fig. 6 is a detail perspective of an attaching plate employed to secure shock absorbing skids to the pontoon bottom and,

Fig. 7 is a detail view of a nut equipped to form an anchorage for pontoon stay wires.

As is best disclosed in Fig. 2 the pontoon is essentially a frusto-conical body or hull, the terminals of which are closed by prow and stern caps of conical shape, and the interior of which is divided into a plurality of airtight compartments by spaced bulkheads. A pair of supporting tubes or rods are provided at the fore and aft portions of the pontoon body for suspending this member beneath the wing of the lower plane of the hydroaeroplane in the manner best disclosed in Fig. 1. Longitudinally and transversely disposed bracing cables connect the supporting members in a manner which will hereinafter be more specifically set forth.

Secured to the body portion of the pontoon is a shock-absorbing member which is formed in the nature of a skid and is extended at its rear terminal a considerable distance beyond the aft end of the body member to provide a flexible tail portion which will engage the surface of the water prior to the landing of the pontoon.

Referring now more specifically to the drawings and more particularly to Fig. 2, the numeral 10 designates the pontoon body or hull, which is preferably formed from sheet metal and is substantially frusto-conical in shape, being tapered from fore to aft. Fore and aft bulkheads are denoted by the numerals 11 and are preferably composed of wood in order to secure a desired thickness and strength with least weight. Intermediate bulkheads 12 may be formed from sheet metal and are provided with suitable marginal flanges whereby they may be brazed or secured by any desired fastening means to the inner surface of the hull 10. A prow cap 14 is provided for the closure of the forward extremity of the pontoon hull and is of sheet metal and formed conically in shape. It is desired in the present construction that the pontoon be possessed of a streamline design, and this prow cap is, therefore, relatively blunt, having a basal diameter which is greater than its axis. An annular flange 15 is provided for the base of this cap and is snugly fitted into the fore end of the hull, being secured in place by rivets or by equivalent fastening devices indicated at 16. An opening 17 is provided in the cap 14 so that access may be had to the interior of the hull at the fore portion

thereof when the rivets 16 are headed. This opening is closed when the pontoon is ready for use by the shield or cover plate 18. A cap forming the stern closure for the pontoon hull is designated by the numeral 19 and will be seen to be also conical and formed of sheet metal, being provided with the customary securing flange at its basal margin for securement to the hull by the rivets 20. In carrying out the streamline design inaugurated by the blunt prow cap 14, this stern cap is so constructed that its axis exceeds the diameter of the base. As in the prow cap, an opening is formed in this cap 19 to grant access to the interior of the stern portion of the hull during the heading of the rivets 20 and this opening is closed when the hull is ready for use by a shield 21 similar to the member 18. For the support of the pontoons upon the wings of the hydroaeroplane both fore brackets and aft brackets are employed. The fore brackets 22 are rods or bars, preferably fashioned from metallic tubes having their lower terminals flattened as denoted by the numeral 24, their upper terminals being flattened and flanged at right angles to the body of the bar. Each of the lower terminals 24 of the bracket rods 22 is apertured to receive a terminal of the supporting rod 26, which extends transversely through the fore bulk head 11, at the approximate horizontal center thereof. The projecting terminals of this rod are threaded for the reception of the securing nuts 27, and are drawn out beyond their threaded portion to produce ears 28 which may readily be apertured for the anchorage of stay wires 29 which extend longitudinally of the hydroaeroplane's wings 30, for the obvious purpose of bracing suspended pontoons. If desired, however, the ears 28 may be as readily formed upon the body of the nut as is particularly illustrated in Fig. 7. Clips 29^a are fastened, in some such manner as riveting, to the flattened in-turned ends 25 of the bracket bars 22 and are attached to receive the upper terminals of diagonally extended, crossed, bracing cables or wires 30, lower terminals of which are secured by metal strips 31 to the terminal portions of the fastening rod 26. The aft bracket is formed of single rod in place of the separate and cross-stayed, bracket arms of the forward structure. Similarly, however, the aft bracket is formed from a metal tubing and includes a pair of arms 32 which are connected by the integral flattened apex portion 33 to form a V. The lower terminals of these arms are flattened for reception of the threaded terminals of the aft fastening rod 34 and the construction employed in this connection is substantially similar to that disclosed with reference to the fore bracket, and is similarly designated. Bracing cables are denoted by

the numerals 35 and 36 and have their terminals respectively secured by suitable clips 37 carried by respective brackets, extending upwardly for points of securement at the top of the opposite bracket, all as is clearly 70 illustrated in Figs. 1 and 2.

It will now be noted that the fore bracket arms 22 are somewhat shorter than the aft bracket 32. Thus, when the pontoon is secured to its wing 30, it is inclined to the horizontal, such inclination being forwardly upward, as has been reproduced in the drawing of Fig. 2. Consequently the pontoon will be inclined to the surface of the water when the hydroaeroplane is alighting 80 with its wings in the normal, substantially horizontal position. This method of attaching the pontoon to the wing is employed that the tail portion of the pontoon skid may first engage the surface of the water, 85 such skid being so mounted as to absorb to a great degree the shock of impact incident to the alighting of the plane. This skid is designated as a whole by the numeral 38 and is formed from a strip of suitable wood in order to have the desired flexibility. The forward end portion of the skid 38 is relatively thick while the tail indicated at 39 is relatively thin, owing to the taper of this member from fore to aft. As 90 shown in the sectional view of Figs. 3 and 4 the bottom of the pontoon is flattened as at 40, to provide a flat bearing surface to the skid member. The thickened fore portion of the member 38 is secured in place by attaching plates 41 such as are illustrated fragmentarily in Fig. 6. As there shown, each attaching plate includes a longitudinal flange 42 provided with a plurality of dependent tabs 43. These tabs are riveted or otherwise secured to the hull as shown in Figs. 1, 2, 3; permitting the flanges 42 to receive between them the longitudinal edges of the skid 38, for securement in the obvious manner. These plates are employed only 100 for a portion of the length of the pontoon for the purpose of attaching the skid, the tail of the latter being left free for flexing. As a guide to normally space the skid from the rear portion of the flattened pontoon 115 body in order that the skid may be forced to exert its shock absorbing qualities by flexing, there is employed the bearing member 44 which extends substantially the entire width of the skid, as is to be clearly seen 120 from an inspection of Fig. 4 and is receivable in contact with a socket plate 45 carried at the bottom of the hull 10 and toward the stern.

A brief résumé of the advantages attendant upon the present pontoon construction, discloses the fact that the minimum amount of head resistance is offered to its passage through any fluid owing to its streamline body, as obtained by the frusto-conical 130

shape of the hull and by the respectively blunt and elongated conical prow and stern caps. Further than this, air-tight compartments are attained by the use of bulkheads of two classes. Bulkheads which are employed for the dual function of supports for the suspending fore and aft brackets are made of a material found to be most suitable for this purpose, while the remaining bulkheads, of which different requirements are made, are most desirable when constructed of another material. The method of mounting the flexible skids, and the shock absorbing qualities of the latter are also features of this invention, as well as the specific bracket construction attached to co-act with the mentioned bulkheads.

While in the foregoing, however, there has thus been illustrated in the drawings and described in the specification such combination and arrangement of elements as constitute the preferred embodiment of this invention, it is desired to emphasize the fact that such minor alterations in the matters of proportion, degree, and the like, may be resorted to in later adaptations of the invention as shall be permitted by the authority of the appended claims.

What is claimed is:

30 1. A wing pontoon for hydroaeroplanes, including a truly frusto-conical hull having the terminal of greatest diameter disposed as its prow, truly conical prow and stern caps closing the terminals of the hull beneath the wing.

2. A wing pontoon for hydroaeroplanes, including a truly frusto-conical hull having the terminal of greatest diameter disposed as its prow, and supporting members of unequal length to suspend the hull beneath a wing with the said terminal of greatest diameter upwardly inclined.

3. A wing pontoon for hydroaeroplanes, including a truly frusto-conical hull, truly conical stern and prow caps closing the terminals of the hull, said prow cap having a basal diameter larger than the basal diameter of said stern cap.

4. A wing pontoon for hydroaeroplanes, including a truly frusto-conical hull, truly conical stern and prow caps closing terminals of the hull, the basal diameter of said prow cap exceeding the basal diameter of said stern cap and the axis of said stern cap exceeding the axis of said prow cap.

5. A wing pontoon for hydroaeroplanes, including a truly frusto-conical hull, truly conical stern and prow caps closing the terminals of the hull, said prow cap having a basal diameter greater than its axis, said stern cap having an axis greater than its basal diameter.

6. A wing pontoon for hydroaeroplanes, including a hull, bulkheads, subdividing the hull into a plurality of air-tight compartments and means connected to certain of said bulkheads for suspending the hull beneath a wing.

7. A wing pontoon for hydroaeroplanes, including a hull, fore and aft bulkheads adjacent the terminals of the hull, intermediate bulkheads co-acting with the first said bulkheads to subdivide the hull into a plurality of air-tight compartments and means connected to said fore and aft bulkheads for the suspension of the hull from a wing.

8. A wing pontoon for hydroaeroplanes, including a hull, a skid attached for a portion of its length to the bottom of said hull, and tail portion for said skid extending aft the stern of said hull and a bearing member carried by said skid to space said tail from said hull.

9. A wing pontoon for hydroaeroplanes, including a hull, transverse bulkheads subdividing the hull into air-tight compartments, rods passing transversely through the hull and through the terminally located bulkheads thereof, and fore and aft supporting members for the hull having extremities connected to respective terminals of the rods.

10. A wing pontoon for hydroaeroplanes, including a hull, rods passing transversely through the hull, fore and aft supporting members having their lower ends removably secured on the terminals of the rods, and bracing elements connecting fore and aft rods with the aft and fore supporting members respectively.

11. A wing pontoon for hydroaeroplanes, including a hull, rods passing through the hull, supporting members having their lower ends engaging respective terminals of said rods, means connected with said rod terminals to serve as a brace anchorage, and bracing elements connecting said means with the pontoon wing.

12. A wing pontoon for hydroaeroplanes, including a hull, formed with a flattened bottom, a skid forwardly attached to said bottom and extending longitudinally therebeyond at the rear, means carried by said skid to prevent contact between the latter and the hull bottom, and a socket adapted to receive said means to facilitate flexing of said skid.

13. A wing pontoon for hydroaeroplanes, including a hull formed with a flattened bottom, a skid forwardly attached to said hull, a bearing block rearwardly carried by said skid and a socket supported on said bottom for engagement with said block in spacing said skid from the bottom for purposes of flexing upon contact with the water.

14. A wing pontoon for hydroaeroplanes, including a hull formed with a flattened bottom, a skid having a width equal to that of the hull, a mounting interposed between the skid and bottom, said mounting including a bearing extending across the skid and a

socket adapted to receive said bearing and extending across said bottom to permit said skid to be readily flexed with respect to said pontoon.

5 15. A wing pontoon for hydroaeroplanes including a hull formed with a flattened bottom, a skid forwardly attached to said bottom and extending longitudinally therebeyond at the rear, and a means interposed 10 between the skid and the hull adjacent the rear end thereof to constitute a pivot bearing for the skid.

16. A wing pontoon for hydroaeroplanes including a hull, a skid of gradually decreasing thickness from its forward end aft, 15 the aft terminal of the skid extending beyond the rear end of the hull, fastening means for the skid at the forward end thereof, and a means for the purpose specified 20 interposed between the skid and the hull at the rear end of the latter.

17. A wing pontoon for hydroaeroplanes including a hull, a skid forwardly attached to the hull and of a length to extend rearwardly beyond the aft end thereof, and 25 means constituting a pivot bearing for the skid arranged between the hull and the skid at the rear end of the hull.

18. A wing pontoon for hydroaeroplanes 30 including a hull, rods passing transversely through the hull respectively adjacent the fore and aft terminals thereof, each rod projecting without the hull at substantially diametrically opposite points, and support

means for the hull secured to the projected 35 terminals of the respective rods and to said wing.

19. A wing pontoon for hydroaeroplanes including a hull, transverse bulkheads subdividing the hull into air-tight compartments, rods passing transversely through 40 the hull and through the terminally located bulkheads, each rod being of a length to extend without the hull at substantially diametrically opposite points, and fore and aft 45 supporting members for the hull having extremities connected to the respective terminals of said rods.

20. A built-up wing pontoon for hydroaeroplanes including a truly frusto-conical 50 hull, truly conical stern and prow caps closing terminals of the hull, the basal diameter of said prow cap exceeding basal diameter of said stern cap and the axis of said stern cap exceeding the axis of said prow cap to 55 effect a substantially streamline pontoon.

21. In a built-up wing pontoon for hydroaeroplanes, an intermediate, truly frusto-conical pontoon section, a truly conical prow cap secured at one end to said intermediate 60 section, and a truly conical stern cap secured to said intermediate pontoon section at the opposite end thereof, the axis of the stern cap exceeding the axis of the prow cap to effect a pontoon of substantially streamline 65 form.

In testimony whereof I affix my signature.
HENRY KLECKLER.
